CASTING MACHINE

Edmund A. Steinbock and August L. Weyhing,
Louisville, Ky.; said Weyhing assignor to said
Steinbock

Application December 18, 1939, Serial No. 309,788

9 Claims. (Cl. 22—65.1)

This invention relates to improvements in a casting machine, such as is used in the dental industry for making dental castings.

The principal object of the present invention is the provision of a casting machine provided with means which prevents the metal melting flame from engagement with the refractory material of which the mold is formed.

Another object of this invention is the provision of a casting machine which confines the casting metal reducing flame to the confines of the crucible until the nugget of metal is molten, thereby preventing harm to the casting mold as was the condition in the past.

Other objects and advantages of the present invention should be readily understood by reference to the following specification when considered in connection with the accompanying drawings and forming part thereof, and it is to be understood that any modifications may be made in the exact structural details therein shown, without departing from or exceeding the spirit of the invention as defined by the appended claims.

In the drawings:

Fig. 1 is a front elevation of one type of a casting machine embodying the improvements of this invention.

Fig. 2 is a rear elevation of certain parts of Fig. 1.

Fig. 3 is an enlarged transverse sectional view, taken on line 3—3 of Fig. 1.

Fig. 4 is a fragmentary, sectional view through certain of the parts of Fig. 3, taken on line 4—4 of said Fig. 3.

Fig. 5 is a view similar to Fig. 3, with, however, the parts in a second position.

Fig. 6 is a longitudinal, sectional view through the parts of Fig. 3, taken on line 6—6 of said Fig. 3.

Fig. 7 is a transverse, sectional view taken on line 7—7 of Fig. 6; and,

Fig. 8 is a view, similar to Fig. 6, but illustrating a modification of the invention.

Throughout the several views of the drawings, similar reference characters are employed to denote the same or similar parts.

The casting machine illustrated in the drawings is known as a centrifugal casting machine. It should be noted that there are several different kinds of centrifugal casting machines wherein the parts operate in a vertical plane, such as illustrated in the drawings, and wherein the parts operate in a horizontal plane, as well as in planes having other angular relations to the supporting base. It should also be noted

that the improvements of this invention have equal application to these different kinds and forms of centrifugal casting machines, as well as to other types of casting machines, and is not to be limited to the specific form shown in 5 the drawings.

The machine specifically illustrated in the drawings comprises a base 10, from which rises a housing formed of a right hand part 11 and a left hand part 12, secured to one another in 10 any suitable or desirable manner. Near the upper end of the housing 11—12, there is provided an aperture for suitable anti-friction bearings in which is mounted a shaft 13. The shaft 13 projects through the housing and has secured to its projecting rear end the hub 14 of an arm, to be described in detail later. In operation, the shaft 13 is to be rapidly rotated, together with the arm secured thereto, and to effect this rotation suitable means are enclosed within the housing 11—12. One such means or mechanism is illustrated in United States Patent No. 1,562,029, issued on November 17, 1925 to Charles E. Larson and Merrill G. Swenson, and since this driving or rotating mechanism forms no part of the present invention, it is deemed unnecessary to further illustrate or describe the mechanism. It should be noted, however, that the shaft 13, and its arm, may be more or less rotated, depending upon the size of the casting to be made. For this purpose, the rotating mechanism is provided with a selectable tensioning device, settable through a shaft, rod or the like, indicated by the reference numeral 15. The mechanism, after being set or positioned by the part 15, is tripped by the rod or trigger indicated in the drawings by the reference numeral 16.

The arm hub 14 has projecting from one side thereof the arm 17, and from the other side the 40 arm 18. The arm 17 is provided at one end with an upstanding portion 19, to which is secured a centering base 20 for the casting mold 21. The casting mold 21 has its front end in engagement with the inner surface of a plate 22, 45 which is secured, as by screws 23 and 24, to a carriage 25. The carriage 25 is in turn secured, as by a screw 26, to the upper surface of a slide 27 mounted on the upper surface of the arm 17.

In order to slidably secure the slide 27 on the 50 arm 17, see Figs. 6 and 7, the said slide has depending from it, at opposite sides, arms 28 and 29, which are connected to one another, below the arm 17, by cap plates 30 and 31. The cap plate 31 has depending from it a boss or lug 32, in 55

which is secured one end of a rod 33. The rod 33 extends from the boss 32, through an aperture 34, in a lug 35, projecting from the arm 17. Beyond the lug 35, the rod 33 is bent to provide a finger piece 36. Surrounding the rod 33, between the cap boss 32 and arm lug 35, is a coil spring 37, abutting on one end with said cap boss 32, and on the other end with the arm lug 35.

10 As will be seen in Figs. 3, 5 and 7, the carriage 25 is U-shaped in cross section, and its arms 38 and 39 are respectively provided, near their upper ends, with aligned seats 40 and 41 for supporting a crucible 42. The crucible 42, as seen 15 in Fig. 6, is dished, and, at its forward end, is provided with a funnel shaped discharge 43 having its discharge opening 44 of substantially the same diameter and in alignment with an aperture 45 in the plate 22. Interposed between the 20 crucible opening 44 and the plate aperture 45 is a baffle, shutter, or the like 46.

The baffle or shutter 46, as seen in Figs. 3 and 7, is so arranged with respect to the plate 22 and carriage 25 as to rest on the upper surface of the 25 carriage arms 38 and 39. The baffle or shutter 46 is provided with an enlarged end 47 and a reduced handle or tail 48, which, when in the normal position of Figs. 3 and 7, projects considerably beyond the plate 22. The attachment of the baffle 30 or shutter 46 to the plate 22 is by means of a pivot screw 49. The baffle or shutter 46, as will later be made clear, is adapted to be actuated from the position of Figs. 3 and 7 to the position of Fig. 5, and in order that no interference be 35 offered by the pivot screw, the screw 46 is surrounded by a short sleeve 50, on which the pivoting movement of the shutter 46 actually takes place, since the screw 49 is screwed home to clamp the sleeve 50 between its head 49 and the face of the plate 22 without impinging on the baffle or shutter 48.

As seen in Fig. 6, the casting mold 21 comprises a metallic ring 51 filled with a refractory material 52, known in the trade as an investment and composed chiefly of plaster and silica, and small percentages of other ingredients, all as is well known in the art. Within this investment material is a cavity 53 conforming in shape and size to the casting to be made. Extending from the cavity 53 is a 50 passage or sprue hole 54 which extends to a depression 55 in the upper end of the mold. This depression 55 is in alignment with the aperture 45 in the plate 22, and the discharge opening 44 of the crucible 42. In order to allow for the dissipation and escape of the air in the cavity 53, when the casting material is discharged thereto, the cavity 53 has extending therefrom an air vent 56.

As is well known, a wax model of the dental 60 casting, or other casting, is first made, which is then invested or surrounded with investment material 52, within the ring 51. This assembly is then placed in a suitable furnace to melt out the wax model and provide the cavity 53, sprue hole 54 and air vent 55. The resulting mold 21 is then ready for the casting machine. The finger piece 36, of the rod 33, is then grasped and operated toward the left, as seen in Fig. 2, to draw the slide 27, and parts carried thereby, including the carriage 25, plate 22 and baffle or trigger 46, from the centering support 20. The mold 21 is then placed on the support 20, at approximately the center thereof, and the rod 33 released, thereby allowing the spring 37 to expand and actuate the slide 27, and parts car-

ried thereby, toward the mold 21 and bring the plate 22 into alignment with the upper or forward end of the mold 21. The force of the spring 47, through the plate 22, yieldably urges the mold 21 against the base 20, which, due to its angular 5 face, centralizes the mold 21 thereon.

A nugget of metal is then placed within the crucible 42 and a blow torch, indicated in Fig. 1 by the reference numeral 57, brought to bear on the nugget for melting same to a state of 10 fluidity.

The metal used for making dental castings, in some instances, is a gold alloy, while in other instances is a chromium alloy. Chromium alloys have, in recent years, become more popular 15 and are becoming wider used. The melting point of chromium alloy, as used today, is around 1800° F., which is considerably in excess of the melting point of the gold alloys heretofore employed.

Prior to this invention, and the use of the baffle, or shutter 46, the flame from the blow torch 20 57 would be directed, after striking the metal nugget through the crucible opening 44 and aligned plate opening 45, against the mold. This flame, in developing the heat necessary for melting chromium alloys, would melt the investment material, both around the sprue hole 54 and the walls of the cavity 53, resulting in a cavity which had a shape other than the necessary and desired shape. The result was a casting 30 which did not match the original wax pattern, or the cavity from which the wax pattern was made. In order to prevent the blow torch flame from attacking the mold, the baffle or shutter 46 is interposed between the crucible discharge opening 44 and the plate opening 45, and confining same to the crucible.

When the metal nugget within the crucible is reduced to a casting state, or a state of fluidity, the tail 48 of the baffle or shutter 46 is contacted, and the shutter actuated in a clockwise direction about its pivot 49, and the crucible 42 moved or shoved forward against the plate 22. The trip lever or trigger 16 is then released to set in operation the arm 17-18 rotating mechanism, 45 thereby throwing the metal from crucible 43 through the now aligned crucible discharge opening 44 and plate aperture 45 into the mold cavity 55, and through the sprue hole 44 into the cavity 53. The arm continues to rotate under its 50 own momentum until the metal in the cavity 53 cools and congeals.

From the foregoing, it will now be appreciated that the mold cavity 53 is kept in its desired shape and condition, and that the resulting casting will 55 conform in all particulars to the size and shape of the cavity 53.

In order to balance the parts carried by the arm 17, the arm 18 is provided, at its outer end, with an upstanding post 58, to which is secured one 60 end of a screw 59 having thereon an adjustable weight 60. The weight 60 is locked in adjusted positions by means of a thumb nut 61. This balancing mechanism forms no part of the present invention, and is disclosed in the above noted 65 patent.

As was pointed out, the mechanism disclosed in Fig. 6 requires the manual shifting of the crucible 42 toward the plate 22 after the baffle or shutter 46 is shifted from the position of Fig. 3 to that of 70 Fig. 5. In order to automatically effect the shifting of this crucible 42, use may be made of the structure disclosed in Fig. 8 for automatically or yieldably shifting the crucible 42. This mechanism, as seen in Fig. 8, comprises a pair of up- 75

standing lugs 62 and 63 on the carriage 25, having aligned apertures therein in which is respectively secured the opposite ends of the rod or bar 64. Surrounding the rod 64 is a coiled spring 65 having one end abutting against the lug 62, and having its other end abutting an arm 66 depending from a slide rod 67. The slide rod 67 projects beyond the carriage 25 where it is provided with a second arm 68, having a pin 69 therein projecting toward and engaging the crucible 42. It will be appreciated that the spring 65, being under tension, will, upon actuation of the baffle or shutter 46, immediately shift the crucible 42 to its inner, final position.

15 In order to prevent the inadvertent removal of the crucible 42 from its carriage seat 40—41, when the baffle or shutter is actuated, the outer end of said crucible may be provided with a small recess or depression 70 receiving the inner end of the pin 69. This connection of the inner end of pin 69 with the recess or depression 70 will act as a latch for holding the crucible in its seat and supplement the weight of the metal in the crucible in retaining same in position.

25 What is claimed is:

1. In a casting machine, the combination of a refractory mold, a crucible, said crucible and mold respectively having a discharge opening and an intake opening in alignment with one another, said crucible being adapted to have a flame directed thereto, and pivotally mounted means between the crucible and mold openings preventing communication therebetween during the time the flame is being directed into the crucible.

35 2. In a casting machine of the class described, the combination with a mold having a cavity therein and a sprue hole extending therefrom, and a crucible having a discharge opening in alignment with the mold sprue hole, of a pivotally mounted baffle between the crucible discharge opening and the mold sprue hole.

3. In a casting machine of the class described, the combination of a mold formed of refractory material and provided with a cavity and sprue hole extending therefrom, a carriage adjacent the mold, a crucible on the carriage and having a discharge opening in alignment with the mold sprue hole, and a pivotally mounted shutter for closing the discharge end of the crucible during the melting of a metal nugget in the crucible.

4. In a casting machine, the combination of a refractory mold having a cavity therein and a sprue hole extending therefrom, a carriage adjacent the mold, a supporting plate on the carriage contacting the mold and having an aperture in alignment with the sprue hole, a crucible on the carriage and having a discharge opening in alignment with the opening in the plate and sprue hole, and a pivotally mounted shutter carried by the plate for closing the discharge opening of the crucible during the melting of a metal nugget therein.

5. In a casting machine, the combination of a refractory mold having a cavity therein and a sprue hole extending therefrom, a carriage adjacent the mold, a supporting plate on the carriage contacting the mold and having an aperture in alignment with the sprue hole, a crucible on the carriage and having a discharge opening in alignment with the opening in the plate and sprue hole, a pivotally mounted shutter carried by the plate for closing the discharge opening of the crucible during the melting of a metal nugget therein, and means for shifting the crucible into engage-

ment with the plate upon removal of the closure means.

6. In a casting machine, the combination of a refractory mold having a cavity therein and a sprue hole extending therefrom, a carriage adjacent the mold, a supporting plate on the carriage contacting the mold and having an aperture in alignment with the sprue hole, a crucible on the carriage and having a discharge opening in alignment with the opening in the plate and sprue hole, a pivotally mounted shutter carried by the plate for closing the discharge opening of the crucible during the melting of a metal nugget therein, and yieldable means for shifting the crucible relative to the carriage into engagement with the plate upon removal of the baffle.

7. In a centrifugal casting machine, the combination of a revolvable arm, means on said arm for supporting a refractory mold which has a cavity therein and a sprue hole, said supporting means including a plate having an aperture in alignment with the sprue hole, a crucible having a discharge opening in alignment with the plate aperture and mold sprue hole, and a baffle pivotally mounted on the plate for normally closing communication between the aligned crucible discharge opening, plate opening and sprue hole during the melting of the metal nugget in the crucible and movable to establish communication through these openings after the metal nugget has been reduced to a state of fluidity.

8. In a centrifugal casting machine, the combination of a revolvable arm, means on said arm for supporting a refractory mold which has a cavity therein and a sprue hole, said supporting means including a plate having an aperture in alignment with the sprue hole, a crucible having a discharge opening in alignment with the plate aperture and mold sprue hole, a baffle pivotally mounted on the plate for normally closing communication between the aligned crucible discharge opening, plate opening and sprue hole during the melting of the metal nugget in the crucible and movable to establish communication through these openings after the metal nugget has been reduced to a state of fluidity, and means for shifting the crucible, plate and mold into contacting engagement with one another to take up the space occupied by the baffle upon removal of the baffle.

9. In a centrifugal casting machine, the combination of a revolvable arm, means on said arm for supporting a refractory mold which has a cavity therein and a sprue hole, said supporting means including a plate having an aperture in alignment with the sprue hole, a crucible having a discharge opening in alignment with the plate aperture and mold sprue hole, a baffle pivotally mounted on the plate for normally closing communication between the aligned crucible discharge opening, plate opening and sprue hole during the melting of the metal nugget in the crucible and movable to establish communication through these openings after the metal nugget has been reduced to a state of fluidity, and means for shifting the crucible, plate and mold into contacting engagement with one another to take up the space occupied by the baffle upon removal of the baffle, including a slide rod, a pin on said slide rod and contacting one of the engaging parts, and a spring for shifting the slide rod.
